COMBINATION PARKING METER TIMER AND COIN HOLDER

John L. Palmer, 2100 N. Sawyer Ave., Chicago, Ill.

Filed Mar. 2, 1961, Ser. No. 64,120

Term of patent 3½ years

(Cl. D52—4)

FIG. 1

FIG. 2

FIG. 3

FIG. 4

FIGURE 2 is a side view;

I claim:

The ornamental design for a combination parking meter timer and coin holder, substantially as shown.
